UNITED STATES PATENT OFFICE.

EDWARD EVERETT TAYLOR, OF AMESBURY, AND CLARENCE PELEG LEONARD, OF CHELSEA, MASSACHUSETTS, ASSIGNORS TO GRAY & DAVIS, OF AMESBURY, MASSACHUSETTS.

LAMP.

SPECIFICATION forming part of Letters Patent No. 764,396, dated July 5, 1904.

Application filed December 29, 1903. Serial No. 187,028. (No model.)

To all whom it may concern:

Be it known that we, EDWARD EVERETT TAYLOR, residing at Amesbury, in the county of Essex, and CLARENCE PELEG LEONARD, residing at Chelsea, in the county of Suffolk, State of Massachusetts, citizens of the United States, have invented new and useful Improvements in Lamps, of which the following is a specification.

10 The object of our invention is the production of a lamp designed for use in connection with automobiles and other vehicles which shall present an artistic and ornamental appearance, be comprised of few parts and some 15 of the parts easily removable, which shall be comparatively cheap in first cost and easy to manufacture, which shall have a plain external surface whereby it may be easily cleaned and polished, and which withal shall constitute 20 a superior means for performing the functions of a perfect lamp.

With this end in view our invention consists in certain novelties of construction and combinations of parts hereinafter set forth 25 and claimed.

The accompanying drawings illustrate an example of the physical embodiment of our invention constructed according to the best mode we have so far devised for the practical 30 application of the principle.

Figure 1 is a top plan view. Fig. 2 is a longitudinal vertical section of Fig. 1. Fig. 3 is a rear end view in elevation. Fig. 4 is a bottom plan view. Fig. 5 is a detail of the 35 means for holding the frusto-conical reflector. Fig. 6 shows the means for uniting the ends of the ring which holds the lens.

The lamp is shaped substantially like a bullet, being conoidal in appearance, and is comprised of three main parts—a shell or body 40 A, frusto-conoidal in shape; the rear portion B, attached to the body portion by the hinge C and fastening device D and constituting the apex portion; and the front portion E, secured to the body portion by hinge F and fastening means G and supporting a lens, as 45 shown.

The numeral 1 designates an opening at the

top of the main body portion; 2, a shield located above and a slight distance from the opening, so as to leave a space between the shield and the body portion for the exit of the gases of combustion; 3, rivets and washers which secure the shield to the body; 4, a lining of asbestos or other suitable material 50 secured to the inner surface of the shield; 4', a wind-deflector located in front of the shield; 5, a series of holes beneath the deflector; 6, means for supporting the lamp consisting of 55 perforated projecting castings located at the sides of the body portion; 7, the base of each casting which engages the inner surface of the body portion and projects through a hole in the side thereof, the said casting being brazed or soldered to the wall of the body; 8, 60 a semiglobular gas-chamber secured to the lower surface of the body; 9, a perforated tubular stem for connection with a gas-generator; 10, a nipple with an opening and having a removable threaded cap; 11, the burner; 12, a tube or duct extending from the burner 65 downwardly into the gas-chamber and approximately to the center of the same; 13, a frusto-conical reflector; 14, the reversely-turned front edge of the reflector; 15, clips 70 soldered at one end to the body portion of the lamp and at the other end bent over to engage the surface of the reflector and to hold it in place, as shown in Fig. 5; 16, two series of 75 holes through the body portion between the gas-chamber and the front edge thereof and through which air passes to the burner, and 17 represents holes in the rear of the gas-chamber.

Referring to the rear hinged apex portion B of the lamp, 18 designates the concavo-convex reflector; 19, a series of holes at the bottom and in the rear of the reflector, and 20 a series of holes at the top arranged to allow air to circulate through the space at the rear 80 of the reflector and reduce the temperature 90 of the same.

Referring to the front portion E, the numeral 21 designates the flanged edge of the same; 22, the lens; 23, a ring concavo-convex in cross-section which holds the lens and 95 is itself held by the flared edge 21, which it

encircles; 24, perforated lugs at the meeting ends of the ring, and 25 is a screw which clamps the ring upon the lens and about the flanged edge of the front portion of the lamp.

5. It will be observed that the lamp is very simple in construction and that parts thereof can with facility be replaced when necessary. The ends of ring 23 may easily be disconnected when a new lens is to replace a broken one, the frusto-conical reflector may be removed by manipulating the clips 15, and the gas-chamber may be cleaned by the removal of the threaded cap.

15 The circulation of the air through the body of the lamp to supply oxygen for combustion and to discharge the products of combustion is provided for by the holes through the body of the lamp and the large opening at the top, as will readily be understood. The deflector 20 4 performs the function of directing the air so that it will pass above the shield.

From the foregoing specific description it becomes obvious that we have produced a lamp which fulfils all the conditions set forth 25 as the purpose of our invention which is ornamental, artistic, of a pleasing shape to the eye, which presents a plain external surface whereby it may be easily cleaned and polished, and which possesses other and desirable 30 characteristics of construction constituting the same a superior means for the purposes intended.

What we claim as new, and desire to secure by Letters Patent, is—

35 1. A vehicle-lamp comprising a frusto-conoidal-shaped shell forming a body portion having an opening at its top, a gas-chamber attached directly to the shell and provided with a tubular stem for connection with a gas-generator, a gas tube or duct extending from the chamber into the shell, a burner connected with said tube or duct, a shield spaced apart 40 from the shell and covering the opening in the top, a wind-deflector attached to the shell 45 in front of the shield, a frusto-conical reflector arranged in front of the burner, a lens located in front of the reflector and hinged to the shell, an apex portion hinged to the body 50 of the shell in the rear of the burner, a concavo-convex reflector arranged in the hinged

portion of the shell, and the rear top and bottom of the shell being provided with a series of perforations for the circulation of air.

2. A vehicle-lamp comprising a frusto-conoidal-shaped shell forming a body portion and having an opening at the top, a shield spaced apart from the shell, directly attached thereto, and covering the said opening at the top, an illuminating-burner secured to a tubular stem adapted for connection with a gas-generator, an apex portion made separate from and secured to the rear end of the shell forming the body portion, a concavo-convex reflector located in the rear of the burner, and a lens hinged to the front of the shell. 65

3. A vehicle-lamp comprising a frusto-conoidal-shaped shell having a hinged apex, a concavo-convex reflector located in the apex, a lens hinged to the front of the shell, an illuminating-burner, a frusto-conoidal reflector 70 back of the lens, and a shield spaced apart from the shell and covering an opening in the top of the shell.

4. A vehicle-lamp comprising a frusto-conoidal-shaped shell having a hinged apex, a concavo-convex reflector located in the apex, a lens hinged to the front of the shell, an illuminating-burner, a frusto-conoidal reflector back of the lens, a shield spaced apart from the shell and covering an opening in the top 80 of the shell, and a wind-deflector on the shell in front of the shield. 85

5. A vehicle-lamp comprising a frusto-conoidal-shaped shell having a hinged apex, a concavo-convex reflector located in the apex, a lens hinged to the front of the shell, a gas-chamber attached directly to the shell, an illuminating-burner in communication with the gas-chamber, a frusto-conical reflector back of the lens, and a shield spaced apart from 90 the shell and covering an opening in the top of the shell.

In testimony whereof we affix our signatures in presence of two witnesses.

EDWARD EVERETT TAYLOR.
CLARENCE PELEG LEONARD.
